MOP HOLDER

Jerome Wank, 672 Nancy Place, North Woodmere, N.Y.
11598, and Robert Fusco, 2727 Ocean Parkway, Brooklyn, N.Y. 11235

Filed Sept. 21, 1965, Ser. No. 87,099

Term of patent 3½ years

(Cl. D9—2)

FIG. 1 is a top view of a mop holder showing our new design;

FIG. 2 is a side view of the mop holder, the other side being substantially identical;

FIG. 3 is a bottom view of the mop holder;

FIG. 4 is a rear view of the mop holder, and
FIG. 5 is a front view of the mop holder.

We claim:

The ornamental design for a mop holder, as shown.
